UNITED STATES PATENT OFFICE.

OSKAR HOFSTRAND, OF BROOKLYN, NEW YORK.

POWER DEVICE.

1,164,185.

Specification of Letters Patent. Patented Dec. 14, 1915.

Application filed April 15, 1914. Serial No. 832,016.

To all whom it may concern:

Be it known that I, OSKAR HOFSTRAND, a citizen of the United States, residing at Brooklyn, in the county of Kings and State 5 of New York, have invented certain new and useful Improvements in Power Devices, of which the following is a specification, reference being had to the accompanying drawings.

10 This invention relates to new and useful improvements in motors and more particularly to a motor which attains its power from the rocking of a marine vessel, the main object of the invention being the provision of a motor of this character which is 15 mounted within the hull of a vessel and is adapted to provide power for any suitable purpose for use upon a ship or vessel.

Another object of the present invention 20 is the provision of a power device of the above character which will possess advantages in points of efficiency and durability, is inexpensive to manufacture and, at the same time, is simple in construction and 25 operation.

With the above and other objects in view, the invention consists in the novel features of construction, combination and arrangement of parts as will be hereinafter referred 30 to and more particularly pointed out in the specification and claims.

In the accompanying drawing forming a part of this application, Figure 1 is a side elevation of a power device constructed in 35 accordance with my invention. Fig. 2 is a transverse sectional view taken on the line 2-2, Fig. 1. Fig. 3 is a side elevation of a slightly modified form of the invention; and Fig. 4 is a side elevation of the pawl 40 and ratchet.

In carrying out my invention, I provide what is known as a balance wheel which in the accompanying drawing is generally indicated by the numeral 1. This wheel is 45 rotatably mounted within a frame 2 which is preferably rectangular in form and is provided at a central portion with a transverse shaft 3, upon which the wheel is mounted. Arranged upon one side of the frame and 50 secured to the shaft is a motor 4, whereby to convey power to the shaft and rotate the wheel 1. The frame 2 is provided at each end with the spindles 5 which are rotatably mounted within the bearings 6 at the upper 55 ends of the standards 7, said standards being securely bolted or otherwise fastened to the

hull of the ship by means of the bolts 8. The spindles 5 are removably arranged within the bearing 6 and securely held in position by means of the plates 9 which are 60 bolted or otherwise secured to the upper ends of the standards in order to retain the spindles in their effective positions.

One of the spindles at one end of the frame projects beyond the standards 7 and 65 mounted thereon is a gear 10 which is adapted to mesh with a similar gear 11 formed upon the inner end of a shaft 12, said shaft being rotatably mounted within upright bearings 13 and provided with a crank 14 70 which is arranged between said bearings. The crank 14 may be connected with any suitable operating mechanism whereby upon the rocking movement of the ship, the reciprocation of the crank will actuate the device to which said crank may be applied. 75

From the above description taken in connection with the accompanying drawing, it will be readily apparent that the operation of my device is as follows:—After the device has been placed in position within the hull of a ship, the motor 4 is started and rotates the wheel 1 at a high rate of speed, so as to impart a substantially gyroscopic action to the wheel and retain the same in 80 a vertical position at all times. Therefore, should the ship be rocking back and forth, the wheel 1 and the gear 10 will be retained in a substantially vertical position, while the standards 13 and 7 will move with the 85 rocking of the ship so that the gear 11 will be moved back and forth over the gear 10 90 to impart a rocking movement to the crank 14.

In Fig. 3 I have illustrated a slightly 95 modified form of the invention which can be readily used in place of the preferred form of device and which will utilize the power obtained from the rocking of the vessel to drive the balance wheel 1. In this 100 form of the invention, a gear 15 is arranged at the end of the frame 2, opposite the gear 10 and is provided with inwardly projecting perforated ears 16 adapted to be rigidly secured to the standards 7 by means of the bolts 17. Projecting outwardly from the frame 2, is a standard 18 in which is mounted a shaft 19 having the gear 20 upon its outer end, said gear being provided with a pivoted pawl 21 adapted to engage with the ratchet 22 mounted upon the shaft 19 to 105 prevent rotation of said shaft in one direc-

tion. Mounted upon the inner end of the shaft 19 is a pinion 23 meshing directly with the pinion 25. The pinion 25 is mounted upon the jack shaft 26 which is journaled in a vertical bearing bracket 27.

Mounted upon the inner end of the shaft 26, is a sprocket 28 which is connected with a similar sprocket 29 by means of a chain 30, the sprocket 29 being mounted upon the outer end of a shaft 31.

Mounted upon the shaft 31 at substantially the central point, is a friction wheel 32 adapted to engage a similar wheel 33 formed upon one end of the shaft 3, whereby upon rotary movement of the shaft 19, the wheel 1 will be rotated. The wheel 32 is slidably mounted upon the shaft 31 and is retained in engagement with the wheel 33 by means of a spring member 34 which is mounted upon the shaft and arranged between a stop collar 35 and one face of the wheel.

Mounted upon the shaft 31 and engaging the opposite side of the wheel 32, is a sleeve 36 to which are secured the governors 37, whereby when the shaft 31 obtains a certain rate of speed, the governors 37 will reciprocate the sleeve 36 upon the shaft and disengage the frictional connection with the wheels 32 and 33.

Mounted upon the outer end of one of the spindles 5 is a suspended hook 38 upon the lower end of which is mounted a weight 39 whereby to retain the balance wheel 1 and the frame 2 in an upright position upon the rocking movement of the vessel.

Relative to the operation of the modified form of the invention, it is to be first explained that the motor 4 is employed only in starting the balance wheel 1 and that after this member has been started, it is driven by the rocking of the ship itself. Since the pinion 15 is fixed with respect to the standard 7, it is obvious that when the ship rocks, the pinion 20 will be rotated. The rotation of this pinion 20 affects the shaft 19, however, only when the ship is rolling in one direction, for on the return movement of the ship the pawl 21 will slide over the ratchet 22. Thus, during each complete oscillation of the ship, one impulse is communicated to the balance wheel 1, through the pinion 15, the pinion 20, pawl and ratchet 21 and 22 and those members which connect the shaft 19 with the balance wheel shaft 3. The rocking movement of the ship will, of course, be imparted through the pinion 38 to the driven shaft 39 in an obvious manner.

While I have shown and described the preferred form of my invention, it will be obvious that various changes in the details of construction and in the proportions may be resorted to for successfully carrying my invention into practice, without sacrificing any of the novel features or departing from the scope of the appended claims.

Having thus described this invention, what I claim is:

1. A device of the class described including upright standards, a frame rotatably mounted between said standards, a balance wheel rotatably mounted within the frame, means for normally retaining said wheel in an upright position, a gear supported at one end upon said frame, a rotatable crank shaft, and means connecting said gear with the crank shaft to impart movement to the latter, as and for the purpose set forth.

2. A device of the class described including upright standards, a frame arranged between said standards and having spindles rotatably mounted within said standards, a balance wheel rotatably mounted within said frame, means for normally retaining said wheel in an upright position, one of said spindles projecting beyond the standard, a gear wheel mounted thereon, a second set of standards, a shaft rotatably mounted therein having a crank formed between the standards, and a gear upon the inner end thereof adapted to mesh with the first gear, as and for the purpose set forth.

3. A device of the class described including upright standards, a frame rotatably mounted between said standards, a balance wheel mounted for rotation within the frame, one of the bearing spindles of said frame projecting beyond the standards, a gear wheel mounted thereon, a second gear wheel adapted to engage with the first gear wheel, means whereby to rotate the balance wheel and impart a gyroscopic action to the same, whereby upon lateral movement of the standards, the frame and balance wheel will be retained in an upright position and the gear wheel simultaneously rotated, as and for the purpose set forth.

4. A device of the class described including upright standards, a frame rotatably mounted between said standards, a balance wheel mounted for rotation within the frame, means for retaining said wheel in an upright position, further means for imparting a rotary movement to said wheel, a gear supported at one end of said frame, a rotatable crank shaft, and means connecting said gear with the crank shaft to impart movement to the latter, as and for the purpose set forth.

5. A device of the class described including upright standards, a frame arranged between said standards and having spindles rotatably mounted within said standards, a balance wheel mounted for rotation within the frame, means for normally retaining said wheel in an upright position, means for imparting rotary movement to said wheel, one of said spindles projecting beyond the standards, a gear wheel mounted thereon, a second set of standards, a shaft rotatably mounted therein having a crank

formed between the standards, and a gear upon the inner end thereof adapted to mesh with the first gear, as and for the purpose set forth.

- 5 6. A device of the character described including relatively fixed standards, a frame rotatably supported by the standards, a balance wheel mounted for rotation in the frame, means connected to the frame for
10 normally maintaining the wheel in a fixed plane, a driven shaft, and means connecting the frame and driven shaft, said driven

shaft being mounted in bearings fixed with respect to the standards, whereby the movement of the standards with respect to the 15 balance wheel causes the driven shaft to be actuated through the medium of the frame.

In testimony whereof I hereunto affix my signature in the presence of two witnesses.

OSKAR HOFSTRAND.
